UNITED STATES PATENT OFFICE.

EDWARD EVELIN CROCKER, OF MCKENZIE, TENNESSEE.

BICYCLE HANDLE-BAR.

SPECIFICATION forming part of Letters Patent No. 603,177, dated April 26, 1898.

Application filed August 31, 1897. Serial No. 650,107. (No model.)

To all whom it may concern:

Be it known that I, EDWARD EVELIN CROCKER, a citizen of the United States, residing at McKenzie, in the county of Carroll and State of Tennessee, have invented certain new and useful Improvements in Bicycle Handle-Bars; and I do hereby declare the following to be a full, clear, and exact description of the invention, such as will enable others skilled in the art to which it appertains to make and use the same.

This invention relates to improvements in bicycles, and has more particular relation to bicycle handle-bars of the adjustable type.

15 The invention consists of the combination, with a bicycle-head, of a casing mounted thereon, a handle-bar constructed of two movable connected sections, a spring - pressed locking-pawl for said sections, and a lever mounted on one of the handle-bar sections and connected to said locking-pawl.

20 The invention also consists of certain other novel constructions, combinations, and arrangements of parts, all of which will be hereinafter more particularly set forth and claimed.

25 In the accompanying drawings, forming part of this specification, Figure 1 represents a perspective view of a head of a bicycle with my invention applied thereto. Fig. 2 represents a central vertical transverse section through the same, and Fig. 3 represents a horizontal section through the containing-casing on the line of the locking-pawl.

30 1 in the drawings represents the head of the bicycle; 2, the containing-casing mounted thereon; 3 3, the handle-bar sections; 4, the locking-pawl, and 5 the operating-handle. Said casing 2 comprises side plates 6 6, connecting top and bottom cross-plates 7 7, which are suitably bolted thereto, so that the interior of the casing may be readily reached when so desired.

35 The handle-bar sections 3 3 may be of any desired shape or conformation and are each provided at their inner ends with flattened segmental portions 8, formed on their peripheries with cog-teeth 9, said teeth of the respective sections intermeshing, so that said 40 sections are caused to move simultaneously when one or the other is rotated upon its pivot-pin 10, which passes through the side

walls of the casing 2. One of the segmental portions 8 is provided with a plurality of locking-apertures 11, arranged in a concentric circle about its pivot and adapted to be engaged by a stud 12 of the locking-pawl 4. Said pawl 4 comprises a flat spring 13, secured at one end to the casing 2, so that its free end will form a yielding support for the stud 12, which latter passes through a suitable aperture formed in the casing 2, so as to enter any one of the apertures 11, as before stated, and thus lock the handle-bars in their raised or lowered or any intermediate position. Said 55 pawl 4 is operated by a bell-crank lever 14, journaled in apertured lugs 15, mounted upon the casing 2. Said bell-crank lever comprises a journal portion 16, a crank-bend 17, having an eye and attached at one end of said journal portion, and a plate or leaf 18, which latter projects under the free end of the spring 13, so as to raise the same when the journal portion 16 is rotated. The crank-bend 17 is connected by a suitable cord or wire 19 to the 60 operating-handle 5, which latter is pivotally mounted upon or near the end of one of the handle-bar sections, so as to occupy a position 65 where it may be readily grasped by the fingers.

70 I do not care to limit myself to the peculiar application of a cord or wire for connecting the bell-crank lever to the operating-handle, as any desired intermediate arrangement of levers or rods may be employed with equal 75 facility.

75 It will be observed from the foregoing description that it is not necessary to stop the machine in order to raise or lower the handle-bars to the desired position, as the operation 80 of the handle 5 will immediately withdraw the stud 12 from the aperture 11, within which it is resting, and thus permit the handle-bars to be raised or lowered to the desired position by the release of said handle.

85 The intermeshing cog-teeth 9 cause both of the handle-bar sections to move simultaneously, so that one of the same cannot be raised or lowered more than the other. The 90 adjustment is rapid and accurate, and the bars may at the same time be readily locked in position immediately upon the desired adjustment being secured.

100 Having thus described my invention, what

I claim as new, and desire to secure by Letters Patent, is—

1. The combination with a bicycle-head, of a suitable casing mounted on the same, two intermeshing handle-bar sections pivotally mounted in said casing, a spring-pressed locking-pawl attached to the casing opposite the section having openings, an operating-handle pivoted to the opposing handle-bar section, and intermediate connections between the operating-handle and pawl, substantially as described.

2. The combination of a bicycle-head, a suitable casing mounted on the same, two intermeshing handle-bar sections pivotally

mounted in said casing, one of them provided with a plurality of openings, a spring-pressed locking-pawl attached to the casing opposite the section having openings, an operating-handle pivoted to the opposing handle-bar section, and intermediate connections between the operating-handle and pawl, substantially as described.

In testimony whereof I have signed this specification in the presence of two subscribing witnesses.

EDWARD EVELIN CROCKER.
